UNITED STATES PATENT OFFICE.

SYDNEY ASHDOWN, OF VANCOUVER, BRITISH COLUMBIA, CANADA.

AUTOMATICALLY-RELEASING HOOK.

992,746.

Specification of Letters Patent. Patented May 23, 1911.

Application filed June 17, 1910. Serial No. 567,421.

To all whom it may concern:

Be it known that I, SYDNEY ASHDOWN, a citizen of the Dominion of Canada, residing at Vancouver, in the Province of British Columbia, Canada, have invented a new and useful Automatically-Releasing Hook, of which the following is a specification.

This invention relates to an automatically releasing hook for use with hauling, hoisting or carrying tackle of any kind in order to effect a saving of time in the release of the load and to dispense with the attendant otherwise required to effect this release.

My object has been to attain this result by a means that is simple in construction and free from any complications that might be liable to derangement in use.

The invention is particularly described in the following specification, reference being made to the drawings by which it is accompanied, in which:

Figure 1 is a side elevation of the hook, the full lines showing it in the position as when a load is on it, and the dot and dash lines in the position of release which the hook automatically assumes when the weight of the load is taken off it, Fig. 2 is an elevation from the front of the hook, Fig. 3, a side elevation showing an addition to meet a possible requirement, and Fig. 4 a cross section on the line A A in Fig. 3.

In these drawings 2 represents the hook which may be of ordinary construction but is preferably made circular in cross section at the several parts of the bend of the hook and is smoothly tapered from a position below the eye to the point. It may also be made of less depth in the hook than is usual that it will more readily slip its load. This hook is freely mounted on a pin 3 secured in an open shackle 4 the sides of which are of such length and spaced apart a sufficient distance to permit the hook to pass freely through the shackle when it is rotated on its pin 3.

Extending from the eye of the hook 2 in a direction opposite to that of the hook and inclined toward the side of the pin on which is the point or opening of the hook, is a counterweight 5 the weight of which is sufficient to overbalance that of the hook, so that when the hook is free from its load it will turn over in the direction indicated by the arrow and will permit the load sling to fall easily out of it.

With this device when a load is in the

hook, the hook will be constrained to assume a position indicated by the full lines in Fig. 1, but when the load is lowered to the ground the pull of the load being removed from the hook the hook will turn over by the preponderating counterweight in which position indicated by the dot and dash lines in Fig. 1 the load will freely escape.

Owing to the desirability of making the hook as shallow as possible in order to facilitate the slipping of the load from it, it may be desirable to provide some means for retaining the hook in its carrying position when the sling of the load is placed in the load but before the full weight is sustained and so avoid the necessity of the hook tender holding the sling in the hook while it is being hoisted. Under ordinary conditions where working in the woods this object is conveniently attained by moving the hook to a position where its counterweight passes through the shackle and by placing a light stick between the weight and the shackle links which device holds the hook with the hook point well up but as soon as the strain comes on the stick is broken or sheared and is no longer required. This device is not, however, always convenient to use and I, therefore, provide a means that will retain the counterweight temporarily in a somewhat exaggerated position of hook engagement and such that when the pull of the load comes on the hook it will release itself from such check. Fig. 3 shows a means by which this can be attained by providing a beveled detent 6 slideable as a plunger against the resistance of a spring 7 within a drilled hole of the counterweight 5 and retained therein by a screwed ring 8 against which the larger dimension of the plunger will bear. This will retain the hook, as shown in Fig. 3, but when the pull of the load comes on the hook the detent 6 will be pressed in against the resistance of the spring 7 and will permit the hook to assume the position shown by full lines in Fig. 1 where it will be free to act in accomplishing the release of the sling, as before described.

Having now particularly described my invention and the manner of its operation, I hereby declare that what I claim as new and desire to be protected in by Letters Patent, is:

1. In an automatically releasing hook, a shackle, a hook having an eye and pivoted

105

110

- at said eye to said shackle, said hook having a counterweight extending beyond the eye opposite the hook, the center of gravity of which counterweight will lie on the hook
- 5 side of a line drawn through the pivotal connection, and the center of gravity of said hook, said counterweight being of greater weight than the hook portion of said hook, said shackle being curved to permit passage of said counterweight, and a yielding means carried by said counterweight to engage said shackle to retain said counterweight in a position between the bars of said shackle.
- 10 2. In an automatically releasing hook, a shackle, a hook having an eye and pivoted at said eye to said shackle, said hook having a counterweight extending beyond the eye opposite the hook, the center of gravity of
- 20 which counterweight will lie on the hook

side of a line drawn through the pivotal connection, and the center of gravity of said hook, said counterweight being of greater weight than the hook portion of said hook, said shackle being curved to permit passage 25 of said counterweight, a yielding means carried by said counterweight to engage said shackle to retain said counterweight in a position between the bars of said shackle, said yieldable means comprising a spring 30 pressed latch held in a recess of said counterweight and having a portion projecting into engagement with said shackle.

In testimony whereof I have signed my name to this specification in the presence of 35 two subscribing witnesses.

SYDNEY ASHDOWN.
